UNITED STATES PATENT OFFICE.

JOHN J. PADBURY, OF ROCKLAND, MAINE, ASSIGNOR TO LIVINGSTON MANUFACTURING COMPANY, OF ROCKLAND, MAINE.

PNEUMATIC TOOL.

1,018,983.

Specification of Letters Patent. Patented Feb. 27, 1912.

Application filed June 26, 1911. Serial No. 635,378.

To all whom it may concern:

Be it known that I, JOHN J. PADBURY, a citizen of the United States, residing at Rockland, county of Knox, State of Maine, have invented certain new and useful Improvements in Pneumatic Tools, of which the following is a specification, reference being had therein to the accompanying drawing.

10 This invention relates to certain new and useful improvements in pneumatic hammers and more particularly to pneumatic chipping tools, the object being to provide a tool in which the initial movement of the 15 piston in its up and down stroke is gradual, caused by the reduced pressure area of the respective ends of the piston which prevents the jerking and vibrating of the tool to a great extent.

20 Another object of the invention is to provide means for cushioning the valve in such a manner that the same will start and stop gradually whereby the pounding of the valve is prevented in order to increase the 25 life of the same and thereby overcome the difficulties now existing with pneumatic tools.

A further object of the invention is to provide a reversible piston in order to allow 30 the same to be reversed when the impact portion becomes worn, thereby increasing the life of the piston two-fold.

A still further object of the invention is to provide a pneumatic tool which is exceedingly simple and cheap in construction 35 and one in which the parts are so mounted that they may be easily and quickly taken apart, and one which is very strong and durable, the parts being so connected that 40 all danger of the same working loose, while in operation, is prevented.

Other and further objects and advantages of the invention will be hereinafter set forth and the novel features thereof defined by the 45 appended claim.

In the drawing—Figure 1 is a longitudinal sectional elevation through my improved pneumatic tool showing the piston in raised position; Fig. 2 is a similar view showing 50 the piston in a lower position and in engagement with the shank of a chipping tool; and Fig. 3 is an elevation partly in section of the valve detached.

Like numerals of reference refer to like 55 parts in the several figures of the drawing.

In carrying out my invention, I employ a cylinder or casing 1 which is provided with an annular reduced portion 2 adjacent its lower end, against which abuts a guide bushing 3 in which is mounted the shank 4 of a tool 5, said shank extending into the contracted portion of the cylinder, as shown, in position to be engaged by the impact portion of the piston, as will be later described. The upper end of the cylinder 1 is externally threaded as shown at 6 on which is mounted the internally threaded sleeve portion 7 of a handle 8 which is provided with a chamber 9 in which is mounted a valve block 10 which bears against a cylinder cap 11 as clearly shown and is locked in position by pins 12, only one of which is shown.

The handle is provided with an inlet passage 13 to which is connected a supply pipe 14 for supplying the motive fluid, said passage 13 communicating with a chamber 15 formed in the valve block in which is mounted a valve 16 having ends 17 and 18 of different sizes forming different pressure areas, and a central annular passage for a purpose later described. The end 17 of the valve is provided with a projection 19 which co-acts with a chamber 20 formed in the cover 11 in order to cushion the valve on its down stroke which also reduces the pressure area 25 on the initial movement of the valve in order to cause the same to move slowly until the projection leaves the chamber.

Extending longitudinally through the wall of the cylinder 1 is a passage 21 provided with ports 22 and 23, the upper end of the passage communicating with a passage 24 leading into the valve chamber 15 and through which motive fluid is adapted to pass and act upon the enlarged pressure area of the valve in order to raise the same. In the opposite wall of the cylinder, a passage 25 is formed which is provided with a port 26 communicating with the cylinder and at its upper end registers with a passage 27 extending through the cylinder cover which, in turn, registers with a passage 28 formed in the valve block, the upper end of said passage registering with the inlet passage 13 formed in the handle in order to allow motive fluid to be supplied to the cylinder.

Mounted within the cylinder 1 is a piston 29 provided with reduced ends 30, one of which forms an impact portion adapted to 110

impact the end of the shank 4 of the tool 5 said end fitting snugly within the reduced portion of the cylinder as clearly shown in Fig. 2, and it will be seen that by this construction, the piston can be reversed in order to bring the opposite end into position to impact the tool. The upper reduced portion of the piston enters a chamber 31 formed in the cylinder cover in order to cushion the up stroke of the piston and communicating with the chamber 31 are diverging passages 32 which register with passages 33 leading into the valve chamber 15 in the valve block and through which live steam or air is adapted to be admitted when in the position shown in Fig. 2 and through which the steam or air is adapted to be exhausted as shown in Fig. 1. An exhaust passage 34 is formed in the valve block which communicates with a chamber 35 surrounding the valve block and is provided with an exhaust port 36. The cylinder is provided with an exhaust port 37 at its lower end through which the motive fluid is exhausted on the down stroke of the piston. An annular groove is formed centrally in the piston 29 forming a passage which registers with the ports 23 and 26 when the piston is in its lower position in order to allow motive fluid to pass into the passage 21 which will act upon the lower end of the piston and the enlarged pressure area of the valve so as to raise the piston and valve.

The operation of the tool is as follows:—
35 Supposing that the piston is in its lower position, as shown in Fig. 2, fluid pressure is supplied through the pipe 14, which may be provided with a throttle valve if desired, into the passage 13 and passes into the cylinder through the port 26 around the groove of the piston through the port 23 into the passage 21. A portion of the fluid pressure passes out of the port 22 under the lower end of the piston and it will be seen that the pressure area of the piston is reduced by the projection being within the reduced portion of the cylinder which causes a slow

initial movement of the piston and at the same time air passes into the valve chamber 15 in the valve block against the large pressure area of the valve which, likewise, has a slow initial movement caused by the projection being within the chamber and as the piston and valve are moved upwardly, the exhaust ports are opened in order to allow the dead motive fluid within the cylinder to be forced out. The upper reduced end of the piston enters the chamber 31 and forms a cushioning action in order to reduce the jar as much as possible. The ports 23 and 26 are then closed by the piston and the motive fluid acts upon the reduced area of the valve and forces the same into the position shown in Fig. 2 and the motive fluid passes through the passages from the valve chamber into the upper end of the cylinder into the chamber 31 so as to produce a slow initial movement which is caused by the reduced area of the piston until it has left the chamber which allows the fluid power to have full pressure upon the piston in order to cause the same to impact the shank of the tool. The dead air within the lower end of the cylinder is forced out through the exhaust 37 and the operation is continued which causes a continuous reciprocation of the piston.

Having described my invention and set forth its merits what I claim and desire to secure by Letters Patent is—

A pneumatic tool having a cover at one end provided with chambers in its inner and outer faces, a piston mounted in said cylinder having a reduced portion co-acting with one of said chambers, and a valve having a reduced portion co-acting with the chamber upon the opposite faces of said cover.

In testimony whereof I affix my signature in presence of two witnesses:

JOHN J. PADBURY.
